UNITED STATES PATENT OFFICE.

ANDREW EGGER, OF RIDGWAY, PENNSYLVANIA.

CALENDAR ATTACHMENT FOR PENCILS.

Application filed June 30, 1924. Serial No. 723,385.

To all whom it may concern:

Be it known that I, ANDREW EGGER, a citizen of the United States, and a resident of Ridgway, in the county of Elk and State of Pennsylvania, have invented a Calendar Attachment for Pencils, of which the following is a full, clear, and exact description.

This invention relates to an attachment for pencils, and has particular reference to one adaptable for the exhibition of a calendar in association with the pencil.

An object of the invention is to provide a simple, efficient and durable attachment for a pencil which by a simple manipulation of a part of the pencil will cause a calendar, normally hidden from view, to be exposed for reference.

Another object concerns the provision of means whereby the attachment can be embodied in the pencil with a minimum requirement as to the alteration of the parts and construction of the pencil.

The invention is illustrated in the drawings, of which—

Figure 1 is the elevation of a pencil with the attachment plate showing the calendar 1 nested;

Fig. 2 is a similar view showing the parts separated;

Fig. 3 is a partial elevation showing the calendar exposed;

Fig. 4 is a section taken on the line 4—4 of Fig. 3 with the calendar in the exposed position;

Fig. 5 is a similar view showing the calendar in its inside position;

Fig. 6 is a longitudinal section through the end of the pencil; and

Fig. 7 is a perspective view of the calendar-carrying sleeve.

The form of the invention shown in the drawings is a preferred form, although it is understood that modifications in the construction and arrangement of the parts and in the character of the materials used may be adopted without departing from the spirit of the invention as set forth in the appended claims.

In its general aspects the invention comprises a calendar-supporting element adapted to be insertible in or associated with a pencil for the purpose of normally retaining a calendar within the pencil out of view,

and one which is capable, by a simple manipulation, of projecting the calendar to an exposed position for reference.

In its preferred embodiment as shown in the drawings, the invention includes a pencil having a stem 1 to the upper end of which a sleeve 2 may be detachably fastened. This sleeve is provided with a slot 3 along one edge of which a flange is downwardly and inwardly bent, as shown in Figs. 4 and 5. Slidable and rotatable within this sleeve 2 is an auxiliary sleeve 4^a. This sleeve is provided with a recess 5 adapted to receive one end of a calendar 6. This calendar may be formed of a plurality of leaves, and when one edge of the calendar 6 is disposed in the recess 5 the metal of the auxiliary sleeve 4^a is crimped around the end of the calendar to hold it in the recess.

The diameters of the sleeves 2 and 4^a are so related that a sufficient space is formed between them when the one is inserted within the other to permit of the disposition of the calendar in this space, as shown in Fig. 5. An ordinary removable cap, such as 7, is adapted to be slipped over the end of the auxiliary sleeve 4^a to act as a means whereby the auxiliary sleeve can be rotated with respect to the main sleeve 2.

Assuming the parts in the position shown in Fig. 5, it will be observed that it is impossible to move the auxiliary sleeve counterclockwise further than the position shown, because the metal of the auxiliary sleeve abuts the flange 4. However, the auxiliary sleeve can be rotated clockwise and in so doing will move the free end of the calendar around in the space between the sleeves until this end of the calendar strikes the sloping face of the flange 4, whereupon the free end will ride up on said flange 4 through the slot 3. Further rotation of the auxiliary sleeve will project practically the entire calendar through the slot for inspection, as shown in Figs. 3 and 4.

By merely turning the auxiliary sleeve in the opposite direction, the calendar can be again nested in the space between the sleeves out of sight.

It is obvious that I have provided a simple, efficient and durable device which can be attached to or associated in any desirable manner with a pencil for the purpose of providing a calendar which can be readily

5 moved into and out of an exhibiting position. In this way the calendar when not in use can be safely preserved from wear and tear and yet the entire pencil is not any more bulky than is the ordinary pencil.

What I claim is:—

1. In combination with a pencil, an attachment in the form of a calendar support, means for normally nesting the calendar 10 out of sight within the pencil, and means for moving the whole calendar at one time to an exhibited position by the manipulation of a part of the pencil.

2. In combination, a pencil having a 15 slotted sleeve, an auxiliary sleeve disposed therewithin and bearing a calendar adapted normally to lie between the sleeves within the pencil, and means whereby the movement of the auxiliary sleeve will cause the

calendar to project through the slot in the 20 first-mentioned sleeve for exhibition.

3. In combination with a pencil having a hollow portion, means for nesting a calendar therewithin, and means for projecting the 25 whole calendar from said sleeve at one time when desired upon the manipulation of a portion of the pencil.

4. An attachment for pencils having a slotted hollow portion, which comprises an auxiliary sleeve to be inserted therein, a 30 calendar supported on said auxiliary sleeve and having a free end, means for nesting the calendar within the hollow portion out of sight, and means for projecting the calendar through the slot in the hollow portion 35 for exhibition when the auxiliary sleeve is manipulated in a predetermined direction.

ANDREW EGGER.
